UNITED STATES PATENT OFFICE

MATTHIAS BROCK, OF BOSTON, MASSACHUSETTS, ASSIGNOR TO UNITED SHOE MACHINERY COMPANY, OF PATERSON, NEW JERSEY, A CORPORATION OF NEW JERSEY.

METHOD OF LASTING SHOES.

1,142,549.

Specification of Letters Patent.

Patented June 8, 1915.

Application filed September 19, 1914. Serial No. 862,554.

To all whom it may concern:

Be it known that I, MATTHIAS BROCK, a citizen of the United States, residing at Boston, in the county of Suffolk and State 5 of Massachusetts, have invented certain Improvements in Methods of Lasting Shoes, of which the following description, in connection with the accompanying drawings, is a specification, like reference characters on 10 the drawings indicating like parts in the several figures.

This invention relates to improvements in methods of lasting shoes, the invention being of especial value in the manufacture of 15 welt and turn shoes in which there is employed an innersole or a sole the margin of which is reduced in thickness to form a feather terminating at its inner side in an upstanding shoulder, lip or rib. 20 In the manufacture of shoes it has become customary to employ in the toe portion of a shoe upper material including sheets of stiffening fabric or leather which are so bulky that they can not be easily 25 conformed as closely to the angular formation presented by the feather and shoulder of the innersole or sole as it is desirable that they should be in order that the upper material may be sewed to the shoulder or 30 lip of the innersole in a manner to produce a tight seam. This difficulty has given rise to the employment of various improved forms of wiping devices in lasting machines, the object of which devices has been 35 to force the upper better into the angle between the feather and the lip of the inner-sole and hold it there while it is being bound to the feather or otherwise secured in place.

For further improving the shape of welt 40 shoes lasted on machines of the hand method type, the ironing device forming the subject matter of United States Letters Patent No. 1,007,270, granted Oct. 31, 1911, to George S. Covell, was invented. That ironing de- 45 vice is an apparatus separate from the machine and is provided with rubbing surfaces shaped approximately to fit the feather, the shoulder and the edge of the innersole or the upper material overlying the same, and 50 said device is heated so that when the shoe is rubbed along said faces the upper is ironed and smoothed and caused by heat and pressure to conform to the surfaces over which it has been lasted. The results ob- 55 tained by this use of the ironing apparatus

as an auxiliary to the hand method lasting machine have been in many respects advantageous and helpful.

A particular object of the present invention is to provide an improved method by 60 which still better results may be secured without sacrificing any of the desirable features and advantages characteristic of the use of the above-mentioned ironing apparatus in connection with lasting machines of 65 the hand method type.

As has been suggested, two handlings of the shoe were required and the ironing operation was performed after the shoe had been lasted and subsequently to the fastening of the upper. The usual fastening for the toes of welt shoes is a binder of wire or other continuous material drawn tightly around the toe and anchored at both ends. When the ironing is performed after the 70 binder has been applied the better conformation of the upper to the contour of the innersole in the angle between the feather and the welt produced by the ironing operation reduces the distance around the end 75 of the toe and therefore loosens the upper with relation to the binder so that the binder no longer holds the upper in place, and consequently there is nothing to hold the upper snugly against the shoulder of the 80 innersole after the ironing operation and before it is sewed so that the effect of the ironing operation is not fully conserved. 85

In accordance with the present invention the ironing of the upper is performed after the upper has been stretched over the last, and it may be after the upper has been carried inwardly over the margin of the inner-sole, but before the fastening operation. The upper is then secured, by the binding 90 or other fastening operation, in a shaped condition in said angle and firmly against the shoulder of the innersole. 95

When the invention is practised with the aid of a lasting machine of the hand method type, by which the upper is stretched progressively by repeated application of pincers to adjacent portions of the upper along the edge of the shoe, the ironing will also be performed progressively, each portion of upper being ironed immediately after it has been stretched and preferably while it is under stretching tension but before it is fully bound in position.

It will be understood that in making shoes 110

with the aid of a machine of this type the binding operation is also performed progressively as the lasting proceeds, the binder being anchored at that side of the toe at 5 which the lasting begins and being maintained under tension as it is wrapped around the toe of the shoe while the lasting progresses.

The invention may be more fully understood in connection with the following detailed description and the annexed drawings which show a lasting machine of the hand method type, with the aid of which machine the invention may be advantageously 10 practised.

Referring to the drawings: Figure 1 shows the forepart of a shoe, in perspective, with the toe to be lasted; Fig. 2 shows a transverse vertical section through the toe 20 of a shoe which is being lasted, with upper being overdrawn and ironed into lasted position; Fig. 3 is a plan view of the shoe illustrated in Fig. 2 showing the operations that are in progress; and Fig. 4 shows the 25 toe portion of the shoe after treatment in accordance with this invention.

In the drawings, 1 indicates a shoe upper including at the toe the usual toe stiffening materials; 2 indicates a last over which 30 the upper is to be stretched and which carries on its bottom face a welt shoe innersole 4, having the thin marginal feather 5 and the upstanding lip or shoulder 6 over which feather and against which shoulder the upper materials require to be shaped to adapt 35 them to receive a welt and to be sewed to the lip or shoulder with a tight seam, it being important that the stitches of the seam enter the shoulder at or near the base thereof 40 of in order to produce a close seam. The upper is stretched over the last by pincers 10 which have an updrawing movement for stretching the upper and an overdrawing movement for carrying the upper inwardly 45 over the innersole. The upper is further forced toward position to be secured by the action of a reciprocating tack block 12 which follows the pincers inwardly across the feather of the innersole.

50 The upper is pressed down upon the feather and inwardly against the shoulder of the innersole and into the angle between the feather and the innersole by the ironing tool 15 which is herein shown as a rotatable 55 disk mounted in a carrier 16 in proximity to an electric heating unit 17 by which the ironing tool is maintained at a high temperature. One portion of the edge of the ironing tool projects from the carrier and 60 into position to overlie and maintain continuous engagement with the upper immediately in the rear of the pincers. By the rotary movement of the ironing tool freshly heated portions are caused successively to 65 emerge from the carrier and to rub the up-

per over the feather with an ironing movement, the edge face of the tool also rubbing the tool against the shoulder and forcing it into the angle between the feather and the shoulder with an ironing movement. The 70 combined effect of the pressure, the rubbing action and the heat is to form or to shape the upper materials to the surfaces of the innersole against which they are pressed with a high degree of efficiency. 75

It will be noted that the ironing operation takes place on each portion of upper while the upper is held stretched by the pincers and by reason of the width of the ironing tool the ironing operation continues 80 while the shoe is being advanced in the direction of feed and the pincers are stretching one or more adjacent portions of the upper by their repeated operations in the progressive lasting of the shoe. 85

For fastening the upper in the position to which it has been stretched and forced by the ironing operation, a binding wire 20 has one end anchored to a tack 21 and, by well-known mechanism contained in the machine, 90 is maintained under tension in a line extending along the edge of the shoe adjacent to the ironing tool where, as the lasting proceeds, it is wrapped around the toe in binding engagement with that portion of the 95 upper which stands up against the shoulder of the innersole.

From the foregoing it will be seen that the upper is stretched and its marginal portion carried inwardly over the margin of an innersole having a feather and upstanding shoulder and then the upper is ironed against and in conformity with the angular formation presented by said feather and shoulder. The ironed portion of the upper 100 is then bound against the shoulder and this 105 succession of steps is repeated upon adjacent portions of the upper to produce progressive lasting.

The novel features of the illustrated lasting machine herein disclosed for the purpose of showing apparatus with the aid of which the present invention may advantageously be practised are not claimed herein 110 but constitute the subject matter of my co-pending application Serial No. 625,670, filed May 6, 1911. 115

Having explained the nature of this invention and how it may be practised, I claim as new and desire to secure by Letters Patent of the United States:

1. That improvement in the art of making shoes which consists in seizing the margin of an upper and stretching the upper and carrying its marginal portion under 125 tension inwardly over the margin of a sole having a feather and upstanding shoulder, ironing the upper under tension by the use of rubbing pressure and heat against and into conformity with the angular formation 130

presented by the said feather and shoulder, and binding the upper against the shoulder into the position and in the condition in which it has been ironed.

- 5 2. That improvement in the art of making shoes which consists in stretching an upper progressively over a last by repeated operations applied to successive portions of the upper, progressively ironing the upper by
 10 forcing each stretched portion successively into position over the feather and against the shoulder of a welt shoe innersole or a turn shoe sole with the aid of a heated ironing tool, and progressively binding the successively stretched and ironed portions of the upper against said shoulder.
 15 3. That improvement in the art of making shoes which consists in stretching an upper progressively over a last by repeated operations applied to successive portions of the upper, progressively ironing the upper by forcing each stretched portion successively into position over the feather and against the shoulder of a welt shoe innersole or a
 20 turn shoe sole with the aid of a heated ironing tool as the lasting progresses, and maintaining the ironing pressure on each portion while another portion is being stretched into place.
 25 4. That improvement in the art of making shoes which consists in progressively lasting the upper around the toe portion of a shoe, progressively ironing the upper

around the toe and progressively securing the upper around the toe, the lasting, ironing and securing being carried on simultaneously upon adjacent portions of the upper as the operations proceed around the toe.

5. That improvement in the art of making shoes which consists in progressively shaping and securing the upper of a shoe over a welt shoe innersole or a turn shoe sole by stretching the upper, ironing the stretched portion of upper into the angle between the feather and the shoulder of the innersole or sole and binding the upper, the operations being repeated in the succession named on adjacent portions of the upper along the edge of the shoe.

6. That improvement in the art of making shoes which consists in stretching the upper over the last and continuing the stretching pull while ironing the stretched upper down upon the feather of a welt shoe innersole or a turn shoe sole and inwardly against the shoulder thereof, and binding the stretched and ironed down upper against the shoulder, all in one continuous operation.

In testimony whereof I have signed my name to this specification in the presence of two subscribing witnesses.

MATTHIAS BROCK.
